UNITED STATES PATENT OFFICE.

HARRY B. CHALMERS, OF DEDHAM, MASSACHUSETTS.

AEROPLANE.

1,145,972.

Specification of Letters Patent. Patented July 13, 1915.

Application filed August 3, 1910. Serial No. 575,218.

To all whom it may concern:

Be it known that I, HARRY B. CHALMERS, a citizen of the United States, and a resident of Dedham, in the county of Norfolk and 5 State of Massachusetts, United States of America, have invented certain new and useful Improvements in Aeroplanes, of which the following is a specification.

My invention relates to aeroplanes, and its 10 object is to provide an apparatus of this kind of simple construction and with a simple system of control.

I will describe my invention in the following specification and point out the novel features thereof in the appended claims.

Referring to the drawings, Figure 1 is a side elevation of an aeroplane made according to my invention. Fig. 2 is a front elevation of the same apparatus, and in Fig. 3 20 I have shown it in plan view. Fig. 4 shows in sectional front elevation a detail of the control mechanism.

Like characters of reference designate corresponding parts in all of the figures.

25 10 designates a horizontal rectangular frame to the front corners of which are affixed a pair of risers 11 which are jointed together at their upper ends and to a stiff longitudinal spar 12. 13 designates another 30 pair of risers which are affixed to the rear corners of the frame 10 and to the spar 12. A transverse spar 14 is also affixed to the risers 11 at right-angles to the spar 12, and rigidly held thereon by braces 15. It may be further secured by means of wires 16 running 35 from its ends to the frame 10. Other wires 17 run from the rear end of the spar 12 to the frame 10. The parts which have just been enumerated form a rigid frame upon 40 which the other parts of the apparatus are supported.

It is to be understood that this structure is shown diagrammatically, and that it may be constructed with as many cross-braces, wires, 45 and other parts as may be found necessary to afford it the required strength.

Supported on the frame 10 are one or two motors 20 which are arranged to drive a propeller shaft 21 on the forward end of 50 which is the propeller 22. If preferred, the propeller may be on the rear end of the shaft in the position indicated by dotted lines in Fig. 1 and designated by 22^A.

30, 30 designate the planes, each of which is built up on a relatively stiff frame of desired shape, the front edge of which is affixed to the transverse spar 14, or is formed thereby. These planes or wings are rotatable about the spar 14 as an axis. They may be loosely pivoted on this spar but are 55 preferably connected thereto with sufficient rigidity to aid in sustaining their own weight. If desired a spar 18, lashed across the uprights 13, may be provided to limit the downward movement of these wings. 60 The rear end of each of these wings is connected by a rod 31 with a tilting lever 32 which is rigidly affixed to the rear end of a shaft 33 supported in fixed bearings on the frame of the apparatus. The forward end 70 of this shaft is provided with a yoke-like structure which forms bearings 34 for trunnions 35 projecting from opposite sides of a tilting support 36 for the control shaft 37. 38 is a gear affixed to this shaft at a point 75 opposite the trunnions. These parts are shown in Fig. 4.

The rock shaft 32 may be tilted to one side or the other by means of this mechanism by merely pushing the control shaft 37 to the 80 left or to the right. This movement will then be transmitted to the two wings 30 simultaneously but in opposite directions through the rods 31 and will cause one of them to be pulled down into some such position as that shown at 30^A in dotted lines in Fig. 1, and the other to be raised in a position such as that shown at 30^B, or to intermediate positions.

40 is a rudder which comprises two rigid planes 41 and 42 fastened together at right-angles to each other and connected to the rear end of the longitudinal spar 12 by a universal joint at 43. From points on opposite sides of the joint 43 on the forward edge 90 of the plane 42 run wires 44. These wires are wound around a drum 45 on the upper end of a vertical shaft 46. Near the lower end of this shaft is fastened a gear 47 which is in mesh with the gear 38 on the control shaft. By this mechanism the rudder may be turned from side to side by rotating the control shaft. Other wires 48 run from the forward edge of the plane 41 under pulleys 49 on the frame 10, and to the tilting support 36 to which they are attached, the one 100 105

from the upper edge of the plane to a point thereon below the trunnions 35, and the one from the lower edge to a point above the trunnions. It may be seen that when the control shaft is pulled backward these connections will cause the rudder plane 42 to be raised, and that when the control shaft is pushed forward the plane 42 will be lowered.

The gears 38 and 47 are of peculiar construction to permit free movement of the control shaft in every direction without getting the teeth of these gears out of mesh.

The manner of obtaining the control movements has been described, and the rest of the 15 operation of the apparatus is obvious. By a single control shaft the operator may tilt the main planes or wings to obtain the proper balance of the machine; he may move the rudder up or down to steer the machine up or down, or he may move the rudder side- 20 wise to guide it laterally.

If desired a vertical stability plane of some such character as that disclosed in a copending application for Letters Patent, 25 Serial Number 575,320, filed by me on the 3rd day of August, 1910, may be added to this apparatus by affixing it to the longitudinal spar 12.

What I claim is:—

30 1. In an aeroplane, a frame therefor comprising a transverse spar in the front thereof and a longitudinal spar running rearwardly therefrom, a pair of supporting wings projecting rearwardly from the transverse spar at either side of the longitudinal spar, a control shaft, a supporting shaft upon which said control shaft is mounted, and connections between said supporting shaft and the wings whereby the positions 35 of said wings may be simultaneously adjusted in opposite directions by moving the control shaft sidewise.

2. In an aeroplane, a frame therefor comprising a transverse spar in the front thereof and a longitudinal spar running rearwardly therefrom, a pair of supporting wings projecting rearwardly from the transverse spar at either side of the longitudinal spar, a horizontal rudder mounted upon the 50 rear end of the longitudinal spar, a control shaft, a supporting shaft upon which said control shaft is mounted, connections between said supporting shaft and the wings whereby the positions of said wings may be simultaneously adjusted in opposite directions by swinging said control shaft as a whole sidewise and other connections between the control shaft and the horizontal rudder whereby the rudder may be moved 55 up and down by swinging the control shaft forward and backward.

3. In an aeroplane, a frame therefor comprising a transverse spar in the front thereof and a longitudinal spar running rearwardly therefrom, a pair of supporting

wings projecting rearwardly from the transverse spar at either side of the longitudinal spar, a rudder mounted upon the rear end of the longitudinal spar, a control shaft, a supporting shaft, a tilting member on the end thereof in which the control shaft is mounted, connections between said supporting shaft and the wings whereby the positions of said wings may be simultaneously adjusted in opposite directions by moving 70 said control shaft sidewise, and other connections between the tilting member and the rudder whereby the rudder may be tilted by moving the control shaft back and forth.

4. In an aeroplane, a frame therefor comprising a transverse spar in the front thereof and a longitudinal spar running rearwardly therefrom, a pair of supporting wings projecting rearwardly from the transverse spar at either side of the longitudinal spar, a rudder having two planes at right-angles to each other pivotally mounted upon the rear end of the longitudinal spar, a control shaft, a supporting shaft, a tilting member on the end thereof in which the control shaft is rotatably mounted, connections between said supporting shaft and the wings whereby the positions of said wings may be simultaneously adjusted in opposite directions by moving said control shaft sidewise, other connections comprising gearing between the control shaft and the rudder whereby the rudder may be moved sidewise by rotating the control shaft, and connections between the tilting member and the rudder whereby the rudder may be tilted by moving the control shaft back and forth.

5. In an aeroplane, a fixed transverse spar, a pair of supporting wings projecting rearwardly from said spar on either side of the longitudinal axis of the aeroplane, said wings being supported to rotate on said spar to assume positions of different inclination relative to the horizontal, a second transverse spar rearwardly arranged to limit the movement of said wings, a substantially vertical controlling shaft supported to be dropped as a whole from side to side, and connections from said shaft to the wings whereby when said shaft is so rocked the wings will be adjusted to positions of opposite inclination.

6. In an aeroplane, a frame therefor comprising a transverse spar and a longitudinal spar running rearwardly therefrom, a pair of supporting wings projecting rearwardly from said transverse spar on either side of the longitudinal spar, a rudder mounted upon the rear end of the longitudinal spar, a controlling shaft, a rock shaft upon which said controlling shaft is mounted to be rocked from side to side, rigid connections between said rock shaft and the wings whereby the positions of said wings may be simultaneously adjusted in opposite direc-

tions by lateral movement of said controlling shaft, connections from the controlling shaft to the rudder operative to effect tilting of the rudder upon longitudinal swinging movement of said shaft, and connections actuated upon rotation of said controlling shaft to move the rudder laterally.

In testimony whereof I have signed my name to this specification in the presence of two subscribing witnesses.

HARRY B. CHALMERS.
